BUILDING STRUCTURE

William Seibert, Haddonfield, N.J., assignor to The
Frostie Company, Camden, N.J.

Filed Mar. 20, 1972, Ser. No. 236,574

Term of patent 14 years

Int. Cl. D25—03

U.S. Cl. D13—1 B

Fig-2

Fig-3

FIG. 4

FIG. 5

FIG. 1 is a perspective view of a building structure embodying my novel design;

FIG. 2 is a front elevational view of the building structure illustrated in FIG. 1;

FIG. 3 is a side elevational view of the building structure illustrated in FIG. 1;

FIG. 4 is a rear elevational view of the building structure illustrated in FIG. 1; and

FIG. 5 is an elevational view of the side of the building structure opposite the side illustrated in FIG. 3.

The broken lines in the drawings are for illustrative purposes only and form no part of the claimed design.

I claim:

The ornamental design for a building structure, substantially as shown and described.
